Primary Examiner — Anhdao Doan*(74) Attorney, Agent, or Firm* — Banner & Witcoff Ltd.(57) **CLAIM**

The ornamental design for a medical imaging device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a medical imaging device showing our new design;

FIG. 2 is a back elevational view thereof;

FIG. 3 is a top plan view thereof;

FIG. 4 is a bottom plan view thereof;

FIG. 5 is a left-side elevational view thereof;

FIG. 6 is a right-side elevational view thereof; and

FIG. 7 is a top, front, left-hand side perspective view thereof.

FIG. 8 is a front view of the medical imaging device having an alternative color scheme;

FIG. 9 is a back elevational view thereof;

FIG. 10 is a top plan view thereof;

FIG. 11 is a bottom plan view thereof;

FIG. 12 is a left-side elevational view thereof;

FIG. 13 is a right-side elevational view thereof; and,

FIG. 14 is a top, front, left-hand side perspective view thereof.

The broken lines shown in the drawings represent portions of the medical imaging device that form no part of the claimed design.
